(57) CLAIM

The ornamental design for a shrimp shoe, as shown and described.

DESCRIPTION

FIG. 1 is a top, left, and rear perspective view of a shrimp shoe, showing my design.

FIG. 2 is a top plan view thereof.

FIG. 3 is a bottom plan view thereof.

FIG. 4 is a left side elevation view thereof.

FIG. 5 is a right side elevation view thereof.

FIG. 6 is a front elevation view thereof; and,

FIG. 7 is a rear elevation view thereof.

A right shoe of the shrimp shoe is a mirror image of the left shoe as shown in FIGS. 1 to 7 and is also claimed.
